UNITED STATES PATENT OFFICE.

WILLIAM S. HASSKARL, OF PHILADELPHIA, PENNSYLVANIA.

FOOTMOBILE.

1,124,897.

Specification of Letters Patent.

Patented Jan. 12, 1915.

Application filed April 29, 1914. Serial No. 835,180.

To all whom it may concern:

Be it known that I, WILLIAM S. HASSKARL, a citizen of the United States of America, residing at Philadelphia, in the county of Philadelphia and State of Pennsylvania, have invented new and useful Improvements in Footmobiles, of which the following is a specification.

This invention relates to trucks, particularly to that class adapted to children's use and bearing such a name as "footmobile."

The object is to provide a device comprising an improved form of truck for the conveyance of children, and adapted to be propelled by the occupant unaided, except when assisted by gravity on a downgrade, at which time it is not necessary for said occupant to exert himself in the least; or the operator may stand upon the running board and propel the device by pushing rearwardly with the foot upon the ground.

Another object is to provide such a device, so constructed as to make it possible for the occupant to either sit or stand upon the same while traveling, and embodying means to prevent the sagging of the running board from the presence of the occupant.

Still another object is to provide an improved method of mounting the steering mechanism, to provide an improved means for removably fixing the steering lever in an upright position, or for permitting the same to assume either a forwardly or rearwardly inclined position; and to provide an improved mounting for the foot rest.

Further objects and advantages of the device are fully brought out in the following specification, when read in conjunction with the accompanying drawings, in which:—

Figure 1 is a side elevation of the preferred embodiment of the invention; Fig. 2 is a bottom plan view of the same; Fig. 3 is a section on the line 3—3 of Fig. 1; Fig. 4 is a section on the line 4—4 of Fig. 1; Fig. 5 is a vertical section of the steering mechanism mounting; Fig. 6 is a perspective view of one of the foot rest supports; Fig. 7 is a perspective view of the steering lever locking sleeve; Fig. 8 is a section on the line 8—8 of Fig. 1; Fig. 9 is a bottom plan view of a modified form of foot rest; Fig. 10 is a side elevation of the same; and Fig. 11 is a perspective view of the foot rest supporting member.

Referring to the drawings, the invention comprises a running board 1, secured at its

rear end to the top of a transversely extending board 3, parallel with which is an upper board 4, the latter forming a seat for the operator or occupant. Said boards 3 and 4 are supported in spaced relation with each other by a pair of frames 5 having integral projections 6 and 7 respectively, to which the boards are secured in any suitable manner. From the bottom of each of the frames 5 extend integral projections 8, provided with studs 9, adapted to receive and rotatably carry the respective wheels 10, said wheels being secured to said studs in any well-known manner, such as by bolts 70 and nuts, or by rivet heads.

Adjacent to the forward end of the board 1, a sectional bearing 15 is secured by means of a flange 16 and screws 17 to said board, said bearing passing through the diagonally extending aperture 18, and being provided with an axial, longitudinally extending bore 19, in which is revolvably mounted the shank 21 of a yoke 22, carrying a pin 23, upon which revolves a wheel 24, said shank being also provided with a circumferential flange 25, which, with the shoulder 26 of the yoke, prevents a longitudinal movement of the shank.

For steering the device, a lever 31 is provided, having handles 32, and bifurcated at its lower end to receive the metallic member 33, said member being held in place by a pin 34 and prevented from oscillating by ferrule-like rings 35, provided with projections 36, either integral or otherwise. Normally surrounding the shank 21 and revolvable thereon is a sleeve 41, shown in Fig. 7, and provided with a longitudinal slot 42, bridged by lateral extensions 43 and adapted to pass along the radially extending ridge 44, formed with the shank 21 until it is free of the same and surrounds the member 33, after which said sleeve is revolved approximately a quarter turn and there removably held by the coöperation of the top of said ridge 44 with the sides of the recess 45. To release the steering lever from the fixed position, the sleeve is raised and turned until the extensions 43 pass over the said ridge.

Substantially midway of the length of the board 1 is a pivot pin 51 which passes downwardly through a horizontally extending member 52 and carries upon its lower end a yoke 53 and wheel 54, as shown in Figs. 1, 2 and 4. Two parallel rods 55,

preferably of wood, are secured in the aligned holes of the respective apertured members 56, illustrated in Fig. 6, said member being provided with a pin 57, and said pins being adapted to move into a U-shaped slot 58 in the brackets 59, which are suitably secured to the under side of the board 1. In this way the rods 55 may be positioned as shown in Fig. 4, or they may be revolved 10 a quarter turn so that they lie parallel with, and centrally beneath the said board 1.

A modified form of foot rest is shown in Figs. 9, 10 and 11. A metallic member 65, having arms 66, and being spaced from the 15 under side of the running board 1 by sleeves or bushings 67, is supported by bolts 68, passing through said bushings, a third or pivotal bolt 69 passing through the member 65 and running board 1 and being secured 20 to the latter. Surrounding the bolt 69 is a foot rest 70 adapted to assume either of the positions shown in full or dotted lines in Fig. 9 and removably maintained in each position by coöperation with the upstanding lugs 71 on the member 65 while being supported by said member, and removable from engagement with said lugs by raising the former upwardly, at which elevation 25 said foot rest may be readily turned to assume the other of the possible positions.

While one preferred embodiment of the invention has been shown and described, it is obvious that numerous changes in the details of construction and operation may be made without departing from the spirit of 35 the invention or from the scope of the appended claim.

I claim:—

A truck comprising a running board, a transversely disposed board secured to one 40 end of the running board, frames connected to opposite ends of the second-named board, a seat fixed to said frames in superimposed relation to the said second-named board, bearings formed on the frames and extending 45 below the second-named board and having journals, wheels rotatably mounted on the said journals, a steering wheel arranged at the opposite end of the running board, a foot rest mounted medially of the running 50 board, a wheel having a bearing swiveled at the point of the foot rest, and means for permitting adjustment of the foot rest laterally with respect to the running board.

In testimony whereof I affix my signature 55 in presence of two witnesses.

WILLIAM S. HASSKARL.
